US00D351910S

United States Patent [19]

Anderson et al.

[11] Patent Number: Des. 351,910

[45] Date of Patent: ** Oct. 25, 1994

[54] PORTABLE MEDICAL ANALYZER

[75] Inventors: **Carter R. Anderson**, Eagan; **Walter L. Sembrowich**, White Bear Lake; **Kee V. Sin**, Lino Lakes; **Frank Solomon**, Plymouth, all of Minn.

[73] Assignee: **Diametrics Medical, Inc.**, Roseville, Minn.

[**] Term: **14 Years**

[21] Appl. No.: **5,165**

[22] Filed: **Feb. 25, 1993**

[52] U.S. Cl. **D24/169**; D10/81;

[57] CLAIM

The ornamental design for a portable medical analyzer,
as shown and described.

DESCRIPTION

FIG. 1 is a perspective view of a portable medical analyzer showing our new design;

FIG. 2 is a top plan view of the portable medical analyzer;

FIG. 3 is a bottom plan view of the portable medical analyzer;

FIG. 4 is a right side elevational view of the portable medical analyzer of FIG. 2;

FIG. 5 is a left side elevational view of the portable medical analyzer of FIG. 2;

FIG. 6 is a front elevational view of a portable medical analyzer of FIG. 2; and,

FIG. 7 is a rear elevational view of the portable medical analyzer of FIG. 2.
